UNITED STATES PATENT OFFICE

EDGAR COCKS, OF LOS ANGELES, CALIFORNIA

CONCEALED BED

Application filed January 17, 1931. Serial No. 509,512.

This invention relates to the class of beds, and has especial reference to disappearing or concealable beds such as are used in apartments or other dwellings.

The invention has for one of its objects the provision of a bed of the indicated character with an improved form of means whereby the bed may be conveniently and easily moved into a down or horizontal position for use, and into an up or out-of-the-way concealable position when not in use, and whereby the bed may be moved as stated, in relation to a wall opening or chamber opening, which opening may be closed by a closure means or door while the bed is in either of its positions, so as to give a tidy and attractive appearance to a room or compartment at all times so far as the use of the bed is concerned.

Another object of the invention is the provision of a bed mounting, retaining and swinging means which is of simple, efficient and substantial design.

The invention will be best understood from a consideration of the following specification taken in connection with the accompanying drawings with the further understanding that the invention is not confined to any strict conformity with the showing in the drawings, since details of construction may be modified and rearranged without departing from the spirit of the invention, the scope of which is limited only by the terms of the appended claims.

In the drawings:

Figure 1 is a sectional view showing in side elevation a bed embodying the features of the invention, the bed being shown in its down or horizontal position for use in relation to an opening in a wall behind which the bed may be concealed;

Figure 2 is a sectional view on an enlarged scale and showing the attached end of the bed;

Figure 3 is a sectional view of the attached end of the bed shown in its up or concealed position;

Figure 4 is a section on the line 4-4 of Fig. 3;

Figure 5 is a section on the line 5-5 of Figure 3.

Referring now more particularly to the drawings, it will be apparent that the invention as shown involves the floor 10 and a wall 11 of a room. The wall 11 has an opening 12 which communicates with a recess, chamber or closet 13. A bed 14 is arranged in relation to the opening 12. The bed 14 will include any preferred conventional frame 15 on which is arranged a mattress 16, indicated by dotted lines, and the usual bedding. The bed 14 also includes a foot end 17 which is attached to the frame 15 to aid in supporting the frame 15 in a horizontal position and which is adapted to swing underneath the frame 15 when the frame is swung into its up or out-of-the-way concealed position within the recess 13. The head end of the bed 14 includes a U-shaped frame constructed of angle irons consisting of a transverse angle iron 18 and vertical angle irons 19 secured respectively to the opposite ends of the angle iron 18. The lower ends of the angle irons 19 are connected with the adjacent ends of the side rails of the bed frame 15 by an angle iron 20. A head end panel 21 is hingedly connected with the angle iron 18 so as to be disposed vertically when the bed is in use, and so as to be folded over the bedding when the bed is in the concealed position. Members 22 are secured respectively to the side rails of the frame 15 and to the angle irons 19 respectively to add strength and rigidity to the frame 15 and the foot end 17. It will be apparent that each of the members 22 is of curved formation and extends upwardly in relation to the frame 15.

In order to mount the bed for swinging movement into a horizontally disposed or down position at one side or at the front of the wall 11, and also into an approximately vertically disposed, up or out-of-the-way concealed position at the opposite side or behind the wall 11 within the recess 13, and also to assist in moving the bed to the said positions and to retain the bed in the positions, there is provided means presently to be described. A frame 23 is arranged within the recess 13 and is secured in any suitable manner to the

floor 10 so as to be fixed or stationary in relation to the opening 12. The frame 23 includes side angle irons 24 having secured thereto respectively horizontally disposed fulcrums or pivots 25 which are in axial alignment. Use is made of an assembly which consists of similar members or arms 26, which are connected together by angle irons 27 and 28 and also by a cross rod 29. Each of the members or arms 26 is of angular formation, the same being greater than a right angle. The members or arms 26 are attached respectively to the fulcrums or pivots 25 for pivotal movement. The bed frame 15 is pivotally attached to the members or arms 26, and this is accomplished by the use of members 30 which are secured respectively to the side rails of the frame 15, and said members having down-turned ends which are attached to pivots 31 carried respectively by the members or arms 26. It will therefore be understood that the frame 15 is swingable on a horizontal axis in relation to the arms 26. The swinging movement of the frame 15 in relation to the arms 26, however, is limited by the provision of extensions 32 on the arms 26, which extensions have laterally projecting ends 33 engaged respectively by the side rails of the frame 15 when the latter is swung upwardly a certain distance from its horizontally disposed or down position. This will cause the arms 26 to move with the frame 15. A suitable number of coil tension springs 34 are employed and each has one end thereof connected with the angle iron 27 as at 35, and its opposite end is connected as at 36 with a transverse angle iron 37 forming a part of the frame 23. Use is also made of a suitable number of coil tension springs 38, each of which has one end thereof connected, as at 39, with the angle 37 and its opposite end connected, as at 40, with the transverse angle iron 18. The springs 34 and 38 function progressively in the swinging of the bed into the up and down positions.

It will be apparent that when the bed frame 15 is in its down position, the arms 26 will serve as supports for the head end of the bed since they will rest on the floor 10, as shown most clearly in Figure 2. When the bed frame 15 is in the down or horizontally disposed position and it is desired to move it to its up or vertically disposed concealed position within the recess 18, it is only necessary to impart an upward or lifting force on the foot end of the bed. The springs 38 come into play in conjunction with this lifting force applied to the foot end, and the bed frame 15 will move on the pivots 31 until the side rails of the bed frame engage the ends 33 of the extensions on the arms 26. This will cause the arms 26 to move upwardly on their fulcrums or pivots 25 which will bring the springs 34 into play. The springs 38 will then become dormant, while the springs 34

will pull the bed frame 15 into its vertically disposed or up position, as indicated in Figure 3. The bed frame 15 will be limited in its movement to the up position by adjustable stops 41 on the frame 23 which are engaged respectively by the angle irons 19. It will also be understood that when it is desired to move the bed frame 15 to its horizontally disposed position or down position, it will only be necessary to pull down on the foot end 17 which will first place the springs 34 under tension thereby counteracting the weight of the movable parts which swing on the fulcrums or pivots 25 which will be followed by the springs 38 being placed under tension counteracting the weight of the movable parts swinging on the pivots 31 until the bed frame 15 is in its down position. The springs 38 plus the weight of the bed frame 15 and the mattress and bedding overcome the retractive force of the springs 34 when the latter are under tension while the bed frame 15 is in the down position.

By reason of the manner in which the bed frame 15 is mounted, it is possible to close the opening 12 through which it swings, when it is in its up or down position. In this connection it is to be observed that the arms 26 are of angular formation, and the intermediate sections thereof may enter notches 5 in the sill 6, and said sections then lying close to the floor in contact therewith, countersunk and disposed crosswise in relation to the sill, thus enabling the opening 12 to be fully closed. The opening 12 may be closed by a suitable closure means in the form of a curtain or roller or sliding door 42, as shown in the present instance. This is an advantage since the opening may detract from the appearance of the room. It is to be understood that two beds may be arranged side by side for movement into a recess sufficiently large to accommodate both of them, in which case two doors 42 may be used and which will move side by side in the wall opening. Where one bed is arranged in relation to a wall opening, as shown in the present instance, the door may move into a pocket or recess 43, as shown in Figure 5.

I claim:

1. In a bed of the class described, in combination, arms mounted to swing on a horizontal axis, a bed frame pivotally attached to the ends of said arms, means connected with the arms at the frame side of said axis and adapted to assist in moving them together with the frame to swing the frame upwardly into an approximately vertical position, means connected with said arms and frame to assist the frame to overcome the action of the first mentioned means when the frame is in a horizontal position and which aids said means to swing said frame upwardly after said frame has been first manually swung upwardly a certain degree from

its horizontal position, and extensions on said arms engaged by said frame limiting the movement of the frame relative to said arms.

2. In a bed of the class described, in combination, arms of obtuse angle shape having their rear ends pivoted to the floor to swing on a horizontal axis, a bed frame pivotally attached to the forward ends of said arms, means connected with the arms at the frame side of said axis and adapted to assist in moving them together with said frame to swing the frame upwardly into an approximately vertical position, and spring means connected with said arms between the ends thereof and also connected with said frame to assist the frame to overcome the pulling effect of the first mentioned means when the frame is in a horizontal position and which assists said means to swing said frame upwardly after said frame has been first manually swung upwardly a certain degree from its horizontal position, and the rear portions of said arms being disposed substantially parallel to the floor and resting thereon when the bed frame is in its horizontal position, to support the adjacent end thereof.

3. In a bed of the class described, in combination, angular members having their rear ends pivoted to a floor to swing on a horizontal axis, a bed frame pivotally attached to the forward ends of said members, whereby the bed frame may be swung into a horizontal position and also into a vertical position, the rear portions of said members resting on the floor so that said members serve as legs for the bed frame when it is in its horizontal position, engageable means on said members and the bed frame allowing the bed frame to have a limited amount of movement relative to said members and also causing the members to move with the bed frame when said means is engaged, upstanding members on said bed frame, and tension springs connected respectively with said upstanding members and said first members between their ends respectively.

4. In a bed of the class described, in combination, angular members having their rear ends pivoted to a floor to swing on a horizontal axis, a bed frame pivotally attached to the forward ends of said members, the provision and arrangement being such that the bed frame may be swung into a horizontal position and also into a vertical position, and the rear portions of said members resting on the floor so that said members serve as legs for the bed frame when it is in its horizontal position, engageable means on said members and the bed frame allowing the bed frame to have a limited amount of movement relative to said members and also causing the members to move with the bed frame when said means is engaged, upstanding members on said bed frame, tension springs connected re-

spectively with said upstanding members and said first members between their ends respectively, and springs connected with said first members respectively to assist in swinging the bed frame upwardly into its vertical position.

5. In a bed of the class described, in combination, a fixed frame, arms having their rear ends pivotally attached to said frame on a horizontal axis, a bed frame pivotally attached to the forward ends of said arms whereby the bed frame may be swung into a horizontal position and also into a vertical position, each of said arms being of angular formation so that the rear portion thereof will rest on the floor when the bed frame is in its horizontal position, springs connected with the fixed frame and said arms between their ends which assist in swinging the bed frame into its vertical position, and tension springs connected with the bed frame and said arms between their ends to assist the bed frame in overcoming the retraction effect of said first springs when the bed frame is in its horizontal position and also to retain the bed frame in its horizontal position.

6. In a bed of the class described, in combination, an angular part pivoted on a floor to swing upwardly and downwardly on a horizontal axis, a bed frame pivotally attached to said angular part to swing relative thereto on a horizontal axis, whereby said bed frame may be swung into a down position supported at one end by said angular part with the latter resting on the floor and also into an up out-of-the-way position, means limiting the swinging movement of the bed frame relative to said angular part when said bed frame is swung upwardly from its down position, spring means connected with said angular part and bed frame to assist in swinging the bed frame upwardly until said limiting means becomes active, a stationary member, and spring means connected with said angular part and stationary member to complete the upward swinging movement of the bed frame into its up position.

7. In a bed of the class described, in combination, a bed frame, an angular part pivotally attached to the underside of one end of said bed frame, said part being pivotally attached to a suitable stationary means such as a floor of a room, spring means connected with the bed frame and said part to assist in swinging the bed frame on its pivotal attachment with said part, additional spring means connected with said part to assist in swinging said part and also the bed frame together, and means to prevent the bed frame from moving relatively to said part while being swung by said last spring means, and said part having rear portions which rest on the floor and thus supporting the adjacent end

of the bed frame when the latter is in a horizontal position.

8. The combination of a fixed floor structure, a part of angular construction having its rear ends pivotally connected with said structure approximately at floor level, a bed frame having one end pivotally connected with the forward ends of said part, said part thus constructed and connected enabling the bed frame to be swung into a horizontal position and also into a vertical position, the rear portions of said part resting on the floor when the bed frame is in its horizontal position to support the adjacent end thereof, ¹⁵ springs each having one end connected with said floor structure a suitable distance above the floor and the other end being connected with said part beyond its pivotal connection first mentioned, and springs each having one end connected with said bed frame and its other end connected with said part between its pivotal connections, said springs serving to assist in moving said bed frame into its vertical position and for retaining the same ²⁵ therein, and also for counterbalancing the bed frame in moving the same into its horizontal position.

9. The combination of a fixed floor structure, a part of angular construction having its rear ends pivotally connected with said structure approximately at floor level, a bed frame having one end pivotally connected with the forward ends of said part, said part thus constructed and connected enabling the bed frame to be swung into a horizontal position and also into an approximately vertical position, the rear portions of said part resting on the floor when the bed frame is in its horizontal position to support the adjacent end thereof, and said end of the bed frame ³⁰

resting on means on said structure when said frame is in its vertical position.

10. The combination of a fixed floor structure, a part of angular construction connected for swinging movement on a horizontal axis approximately at floor level in relation to said structure, a bed frame having one end pivotally connected with the forward ends of said part, said part thus constructed and connected enabling the bed frame to be swung into a horizontal position and also into an approximately vertical position, the rear portions of said part resting on the floor when the bed frame is in its horizontal position to support the adjacent end thereof, and said end of the bed frame resting on means on said structure when said frame is in its vertical position. ⁷⁰ ⁷⁵

11. The combination with a bed frame, of a fulcrum approximately at floor level, means on said fulcrum mounting said frame for swinging movement into a horizontal down position and also into an approximately vertical up position, and also serving to support one end of said frame when in its down position, said means allowing relative movement of the frame with respect thereto when swinging the frame up and down, means limiting the amount of relative movement of the frame as it is being swung up, a set of springs connected with said frame and first means in such a manner as to aid in lifting the frame as the latter is being swung up, a fixed member, and a second set of springs connected with said fixed member and first means in such a manner as to complete the swinging of the bed frame into its up position after said first set of springs become dormant. ⁸⁰ ⁸⁵ ⁹⁰ ⁹⁵ ¹⁰⁰
